FOREIGN PATENT DOCUMENTS

DE 2204784 A1 8/1973
FR 2358128 B1 11/1980*Primary Examiner* — Ricky Pham(57) **CLAIM**

We claim the ornamental design for a casegood corner, as shown and described.

DESCRIPTION

FIG. 1 is a front perspective view of a casegood corner, according to one embodiment;

FIG. 2 is a top perspective view of a casegood corner of FIG. 1;

FIG. 3 is a front view of a casegood corner of FIG. 1;

FIG. 4 is a rear view of a casegood corner of FIG. 1;

FIG. 5 is a left side view of a casegood corner of FIG. 1;

FIG. 6 is a right side view of a casegood corner of FIG. 1;

FIG. 7 is a top view of a casegood corner of FIG. 1;

FIG. 8 is a bottom view of a casegood corner of FIG. 1;

FIG. 9 is a front perspective view of a casegood corner, according to a second embodiment;

FIG. 10 is a top perspective view of a casegood corner of FIG. 9;

FIG. 11 is a front view of a casegood corner of FIG. 9;

FIG. 12 is a rear view of a casegood corner of FIG. 9;

FIG. 13 is a left side view of a casegood corner of FIG. 9;

FIG. 14 is a right side view of a casegood corner of FIG. 9;

FIG. 15 is a top view of a casegood corner of FIG. 9; and,

FIG. 16 is a bottom view of a casegood corner of FIG. 9. The dashed lines are for purposes of illustrating environmental structure and form no part of the claimed design.
